Primary Examiner — Angela J Lee(74) Attorney, Agent, or Firm — Meunier Carlin & Curfman LLC(57) CLAIM

The ornamental design for a canopy light, as shown and described.

DESCRIPTION

FIG. 1 is a perspective view of a canopy light, showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the figures are included for the purpose of illustrating portions of the canopy light which form no part of the claimed design.
